UNITED STATES PATENT OFFICE.

ROBERT V. PROCTOR AND HARRY M. SCHaab, OF YOUNGSTOWN, OHIO, ASSIGNORS TO THE COMMERCIAL SHEARING & STAMPING COMPANY, OF YOUNGSTOWN, OHIO, A CORPORATION OF OHIO.

PALLET FOR TILES.

Application filed March 31, 1925. Serial No. 19,608.

The present invention relates broadly to pallets and the manufacturing of tiles, porcelain ware, abrasive wheels and the like, and more particularly to pallets of the character adapted for use in the manufacture of the so-called terra cotta tiles or blocks, although the utility of the invention is not limited to use with terra cotta bodies.

At the present time the manufacture of terra cotta tiles, the word tiles being used in its generic sense as definitive of architectural shapes, face blocks, lintels, sills and the like, involves many difficulties. Not infrequently the individual tiles weigh as much as 500 pounds, so that the mere physical handling thereof presents a considerable problem. In addition to this, a single order frequently requires a number of widely different shapes or designs, thereby necessitating the use of special molds for each tile. Ordinarily the tiles are formed in plaster of Paris molds, by hand, it being customary to make them hollow in back and provide them with openings serving not only to facilitate handling but also to permit air circulation during the driving of the tiles.

The tiles as now formed by hand are subsequently inverted onto wooden pallets, and then touched up to cure any defects which may have occurred due to faulty molding or the like. The pallets, either with or without the tiles thereon, are commonly moved from point to point by dragging them over the floor. These heavy tiles on the wooden pallets are then sometimes put into humidity driers where they are permitted to remain in the neighborhood of 24 hours. During at least a part of this time they are subjected to a temperature in the neighborhood of 180° F. and to a humidity of from 60 to 70 per cent. After a predetermined interval, the steam is shut off, and dry air is directed into the driers. During the period of treatment with the dry air, the heat in the tiles tends to drive out the moisture. As this moisture is driven out, the tiles tend to shrink, the shrinkage being frequently as high as three-quarters of an inch to the foot. As the tiles are not infrequently several feet in length, it will be apparent that the shrinkage becomes a factor of considerable importance.

With the wooden pallets, the two essentials of ease of relative movement between the tiles and the pallets and uniform drying, are not possible. The bottom portions of the tiles resting on the wooden pallets, and the inside of the core openings do not get proper air circulation and therefore there is a slower rate of moisture loss in these portions than in the remainder of the terra cotta body. Also, after a very short time the supporting surfaces of the wooden pallets become rough or warped, thereby preventing easy sliding of the blocks thereon during the shrinking operation. It frequently happens under these conditions that at least some of the tiles are of poor quality.

The present invention has for certain of its objects the obviating of the difficulties and objections heretofore encountered in the manufacture of terra cotta tiles, whereby a better quality of product is made possible, and the length of life of the pallets and ease of handling the same is increased.

Fundamentally, the present invention involves the use of steel pallets of such construction as not only to facilitate handling and to impart the necessary strength, but such as will also insure greater ease of movement of the tile during shrinkage, better air circulation to thereby establish a more nearly uniform condition of drying, and increased heat transfer to those portions from which the moisture expulsion has heretofore been comparatively slow.

In the accompanying drawings, there are shown for purposes of illustration only certain preferred embodiments of the present invention, it being understood that the drawings do not define the limits of our invention, as changes in the construction and operation disclosed therein may be made without departing either from the spirit of the invention or the scope of our broader claims.

Due to this high shrinkage, and to the size

Figure 1 is top plan view of a portion of

a pallet embodying the present invention, the drawing illustrating substantially half of a complete pallet;

30 In carrying out the present invention it is necessary to bear in mind the essentials of strength, in order to carry the heavy loads imposed on the pallets; durability, in order to permit rough handling of the pallets 35 without danger of breaking or bending; shape, to facilitate handling and sliding over a floor or the like while permitting stacking of the pallets; and design, whereby the desired air circulation and heat transfer are both obtained.

In Figure 1 of the drawings there is illustrated an embodiment of our invention which has been found highly desirable in the manufacture of certain types of terra 45 cotta tiles. This embodiment comprises a main body portion 2 having its upper surface shaped to provide a supporting surface for a tile during certain of the steps of the manufacture thereof. In order to provide 50 the necessary strength for the main body, and prevent sagging or twisting thereof, the body may be formed with a plurality of stiffening ribs 3 extending lengthwise thereof and preferably pressed downwardly out

55 of the plane of the supporting surface. In order to permit circulation of air freely to the interior of the tile and throughout the hollow portions thereof, the main body of the pallet may have a plurality of openings 60 4 formed therein. It will be understood that the location of these openings will depend to some extent upon the character of the tile to be produced thereon, it being necessary in certain cases to provide certain portions of the pallet without perfora-

tions in order to facilitate the production of a smooth finished edge portion on a tile. It is within the purview of our invention, therefore, that certain portions of the body may be perforated while other portions are 70 free from such perforations.

Extending transversely of the pallet adjacent each end thereof are depressions 5 serving not only to stiffen the pallets against sagging, but also providing recesses for the 75 reception of legs on adjacent pallets when the pallets are stacked, to thereby prevent relative movement as will hereinafter be more fully pointed out.

The side edges of the pallets are preferably 80 turned downwardly to provide flanges 6 and then upwardly to form smooth rounded lower edges 7 permitting an operator to grasp the pallet without danger of injury to his hands and also stiffening the flanges 85 and further strengthening the pallet body. The ends may be constructed similarly to the sides, but are preferably reinforced by a rolled flange 8 providing a better gripping edge and further facilitating handling of the 90 pallets, it being customary during certain operations for the operators to lift the same from the ends.

In some cases it is required that the pallets shall be supported such a distance above 95 the floor as to permit the passage of a lifting truck therebelow. This requires supporting legs of a height sufficient for this purpose, and so spaced as to permit the free 100 passage of the truck therebetween. In the construction shown in Figure 1, the legs are illustrated as comprising U-shaped straps of metal having their upper ends 9 welded or otherwise secured to the side flanges 6 and having a continuously extending reinforcing 105 rib or corrugation 10. Preferably the sides 11 of the legs converge in a downward direction whereby the width of the base is less than the width of the pallet thereby 110 permitting the same to freely engage the recess 5 in an adjacent pallet during the stacking of the pallets in superimposed relationship. Due to the desirability of such an operation, it will be apparent that it is essential to secure the upper ends of the legs 115 to the body of the pallet immediately below and substantially in the vertical plane of the recesses 5, as clearly illustrated in Figures 1 and 3.

In Figure 5 of the drawings there is illustrated another form of our invention in which the main body of the pallet is composed of a series of strips 12, each of the strips having reinforcing side flanges 13. The flanges 13 for the outer edges of the two outer strips are conveniently formed by bending the metal downwardly and upwardly as before described to provide rounded lower edges 7. The ends of the strips are likewise preferably reinforced by 130

rounded flanges 8' forming convenient gripping portions.

The strips composing the body are assembled in spaced relation, and held in this position by legs 14 which may conveniently comprise pressed metal sheets having openings 15 and having a continuous reinforcing bead 16 extending longitudinally of the leg and transversely thereof between the openings. At its lower end the leg may have a laterally extending foot 17 providing a larger supporting surface. The upper end of the leg may be welded in position between the side flanges of the two outer strips and may be cut away intermediate its ends to receive the downturned flanges 13, all of which may be welded if desired.

The form of our invention illustrated in Figure 8 is similar to that shown in Figures 1 to 4, both inclusive, with the exception of the construction of the supporting leg. In accordance with this illustration, the supporting leg may be formed by channels 18 suitably secured at their upper ends to the side flanges below the recess 5 and projecting downwardly therefrom. Each of these channels is provided with a series of openings 19 adapted to receive a transversely extending pin 20. The foot of each leg may be formed by a U-shaped strap 21 having upstanding ends 22 of a width adapted to pass freely between the side flanges of the channels 18 and having aligned openings to receive the opposite ends of the pin 20. Due to this construction the overall height of the legs may be adjusted as required for different trucks, tiles of different dimensions, or different types of operations.

In all of the forms of the invention heretofore described, the lower or supporting surfaces of the legs are of such construction as to permit a pallet to be bodily slid along a floor or other surface without injury thereto while providing the necessary clearance for the passage of a lifting truck therebetween. The edges of the pallets are of such construction that they may be readily gripped by an operator, the ends being shaped to facilitate handling and stacking. In the form illustrated more particularly in Figures 5 and 6 of the drawings, the individual strips may or may not be perforated as desired, it being obvious that the spaces provided between their adjacent edges insure ample room for the free circulation of air.

In Figure 9 of the drawings there is shown a form of our invention more especially adapted to transportation by sliding along the surface of a floor or the like and having shorter legs. Pallets of this type may be constructed to replace ordinary wooden pallets where lifting trucks have not customarily been utilized. Such pallets may comprise a body 24 which may be either perforated

throughout or at the desired points, as required, and which has a continuous flange 25, the continuity being effected by welding the adjacent edges of the downturned flanges at the sides and ends as indicated at 70 26. This continuous flange tends to prevent twisting of the pallet about its diagonals. The blank from which the pallets are formed may be provided with projecting portions adapted to form legs 27 at suitable 75 points, the lower ends of the legs being turned inwardly to provide feet 28. At certain points along its sides or ends, or both, the downturned flanges 25 may be provided with a series of notches or recesses 80 29 adapted to facilitate the engagement with the pallet of a hook or other object used in sliding it along, and prevent such hook from slipping toward either end of the pallet.

The form of the invention illustrated in Figure 10 differs from that in Figure 9 only in the provision of rounded corners 30 whereby a continuous integral downturned flange 31 is made possible. It will be understood that the forms of our invention 85 illustrated in Figures 9 and 10 may be reinforced by ribs or corrugations located at any desired points, as heretofore pointed out.

In Figures 11 and 12 of the drawings 90 there is illustrated a form of pallet similar to that shown in Figures 5 and 6, with the exception of the particular method of reinforcing the individual strips and the construction of the legs. We have found that 100 it is possible to provide strips of certain standard widths adapted to be assembled in different relationship to produce pallets of different widths. In Figures 5 and 6 the three strips are shown as being of similar 105 construction, while in Figures 11 and 12 the center strip 30 is illustrated as being narrower than the two side strips 31. By providing standard strips of different widths, it will be readily apparent that they 110 can be assembled in any desired relationship, thereby facilitating the formation of pallets of different dimensions as required.

The edges and ends of the pallets may be similarly reinforced by providing downturned flanges 32 having their bottom edges 33 curved inwardly and upwardly to provide a rounded lower edge, expediting gripping and handling of the pallets. The legs 34 may be constructed of sheet material having cut-away portions 35 for the reception of the side flanges 36 and having notches 37 for the reception of the edge flanges 32. The notches 37 are preferably so dimensioned that the rounded lower edges 35 of the flanges 125 32 will rest in the notches and be further reinforced thereby. This is highly desirable, as frequently the pallets are bodily rolled over with a tile supported thereon, and during such operations the notches form 130

4
a substantial reinforcement. The legs may be welded or otherwise secured to the strips as desired.

In order to facilitate sliding of the pallets over a floor or other surface, the lower ends of the legs are turned upwardly, and the ends 38 are in turn bent up out of the plane of the main portion of the bottom of the legs, whereby the legs may act as runners without fear of engagement with upstanding projections or irregularities in the floor surface.

In our divisional application, Serial No. 88,829, filed February 17, 1926, there is specifically disclosed and claimed the pallet construction of Figures 1, 2, 3 and 8 of the present application.

The advantages of the present invention arise from the provision of sheet metal pallets of a size and strength adapting them for use in the manufacture of terra cotta tiles, and facilitating transportation of the pallets and movement of the tile relatively to the pallets during the drying thereof.

Further advantages of the present invention arise from the method of curing or drying tiles and similar articles on metallic pallets as distinguished from wooden pallets, whereby it is possible to provide relatively smooth supporting surfaces and obtain high heat transfer with efficient air circulation.

We claim:

1. As an article of manufacture, a pallet comprising a metallic supporting body having at least one opening therethrough for the circulation of air, means for reinforcing said body throughout the central and edge portions thereof to prevent bending, and supporting legs projecting downwardly from said body, substantially as described.

2. As an article of manufacture, a pallet comprising a metallic supporting body having at least one opening therethrough for the circulation of air, means for reinforcing said body throughout the central and edge portions thereof to prevent bending, and widely spaced supporting legs projecting downwardly from said body, said legs being of a height as to permit the insertion of a lift truck below the body, substantially as described.

3. As an article of manufacture, a pallet comprising a metallic supporting body having at least one opening therethrough for the circulation of air, means for reinforcing said body to prevent bending thereof, and supporting legs projecting downwardly from said body, said body having at least portions of its periphery shaped to reinforce the pallet and providing broadened surfaces to facilitate gripping thereof by an operator, substantially as described.

4. As an article of manufacture, a pallet comprising a metallic supporting body having at least one opening therethrough for

the circulation of air, means for reinforcing said body to prevent bending thereof, and supporting legs projecting downwardly from said body, said legs each having reinforcing means effective vertically thereof, substantially as described.

5. As an article of manufacture, a pallet provided with a supporting surface formed of a plurality of spaced bodies, and legs common to all of said bodies, said legs having cutaway portions cooperating with said bodies, substantially as described.

6. As an article of manufacture, a pallet provided with a supporting surface formed of a plurality of spaced strips, each strip having reinforcing means therefor, and legs cooperating both with the bodies of said strips and the reinforcing means therefor, substantially as described.

7. As an article of manufacture, a pallet provided with a supporting surface formed of a plurality of spaced strips, each having reinforcing side flanges formed thereon and protecting downwardly therefrom, and legs shaped to extend upwardly between said flanges, substantially as described.

8. As an article of manufacture, a pallet provided with a metallic supporting surface, stiffening flanges for said surface, and legs shaped to extend between said flanges and projecting downwardly below said flanges, substantially as described.

9. As an article of manufacture, a pallet provided with a metallic supporting surface, stiffening flanges for said surface, and legs projecting downwardly below said flanges, said legs cooperating at their upper ends with said flanges and the under side of said surface, substantially as described.

10. As an article of manufacture, a pallet comprising a metallic supporting body, means for reinforcing said body throughout the central and edge portions thereof to prevent bending, and supporting legs projecting downwardly from said body, said legs being of a height and being so spaced as to permit the insertion of a lift truck below the body, substantially as described.

11. As an article of manufacture, a pallet comprising a metallic supporting body, means for reinforcing said body to prevent bending thereof, and supporting legs projecting downwardly from said body, said legs each having reinforcing means effective vertically thereof, substantially as described.

12. As an article of manufacture, a pallet comprising a supporting surface formed of a plurality of strips, each strip having reinforcing means therefor, and legs cooperating both with said strips and the reinforcing means therefor, substantially as described.

13. As an article of manufacture, a pallet provided with a supporting surface formed with a plurality of longitudinally extending reinforcing means, at least some of said reinforcing means comprising downturned flanges, and supporting legs for said surface shaped to extend upwardly within said flanges, substantially as described.

14. As an article of manufacture, a pallet provided with a supporting surface formed with a plurality of longitudinally extend-

ing reinforcing means, at least some of said reinforcing means comprising downturned flanges, and supporting legs for said surface shaped to extend upwardly within said flanges, said supporting legs having vertically effective reinforcing means, substantially as described. 15

In testimony whereof we have hereunto set our hands.

ROBERT V. PROCTOR.
HARRY M. SCHaab.
